UNITED STATES PATENT OFFICE.

JAY A. FREIDAY, OF EAST ORANGE, NEW JERSEY, ASSIGNOR TO THOMAS E. MURRAY,
OF BROOKLYN, NEW YORK.

BOILER.

Application filed March 12, 1927. Serial No. 174,736.

This invention aims to provide certain improvements applicable especially to high duty boilers. The accompanying drawing illustrates in a single figure a longitudinal vertical section of a boiler embodying the invention.

The boiler includes the usual overhead banks 1 and 2 of approximately horizontal water tubes with headers 3 and 4 at the lower ends and 5 and 6 at the upper ends connected to the steam drum 7 from which the steam passes through a superheater 8 to the point of consumption. Baffles 9, 10 and 11 direct the gases in the desired course over and between the several tubes. This is a common arrangement and various modifications of that illustrated may be utilized with this invention.

It has been the constant effort of designers to operate such boilers at higher and higher speeds or ratings, so as to get the maximum quantity of steam per hour out of a given installation, and this has involved extending the stoker or other fuel supply devices. To get the maximum stoker capacities this part of the apparatus has been extended clear across to the back of the furnace or combustion chamber and even beyond the normal line of the back wall. My invention provides a structure which facilitates the use of such an extended stoker. The front wall 12 of the furnace has a feed opening 13 adjacent to which is the hopper 14 for coal and the feed mechanism indicated diagrammatically at 15 from which extends the stoker grate 16 sloping gradually downward to the rear and dumping the ashes and cinders finally into an ash trough 17. In order that the stoker grate may be made as long as possible from front to back, I have provided a rear furnace wall 18 which is offset considerably beyond the rear wall of the upper structure as marked by the headers 5 and 6. The wall 18 extends vertically to about the top of the combustion chamber where it meets an arch 19, the inner end of which is curved inward as at 20 to provide for a certain amount of expansion and connects with the upper structure. This wall is exposed to very high temperatures from the radiant heat of the burning fuel. I prefer to protect it and at the same time to utilize the heat to greatest advantage by lining it with a wall of water tubes 20 extending vertically up the face of the vertical portion 18 and tubes 21 along the inner face of the portions 19 and 20. These tubes have head-

ers 22, 23 and 24 in the locations indicated, the latter communicating with the headers 5 so as to provide a direct and easy circulation of steam from the lower tubing to the steam drum; the cross header 25 at the front which receives water from the steam drum, having outside connections as usual leading down to the drum 22 at the base of the rear wall. The intermediate drum 23 may be omitted though it probably facilitates circulation.

Such an offset wall 18 and arch 19 (either with or without the water lining) provides a very simple and convenient structure which permits the making of the stoker of maximum length. When the water tube lining is added we get an even more beneficial result from the increased stoker size, by reason of the effect of the radiant heat on the water in these tubes.

It has previously been proposed to carry the dumping end of the stoker and the ash pit into a shallow recess at the back of the furnace, practically the whole space for combustion and mixture of the gases being of the same cross-sectional area as that of the overhead tubing or less.

According to the present invention, however, the offset rear wall extends to a considerable height above the rear end of the stoker and practically to the rear ends of the overhead tubes, allowing only space at the top for the inclined arch and expansion bend, and extending downward well below the front wall. Thus we have a comparatively high combustion chamber of the full width of the overhead bank of the tubes and of greater length than such tubes throughout substantially the full height of the chamber, and of a greater height at the back than at the front, so as to effect thorough combustion and uniform admixture of the gases before their passage through the overhead tubes.

The shape illustrated has also an advantage in connection with the ash pit at the base of the rear wall. A certain amount of cold air enters from the ash pit and is carried up in the current of gases. With the shape illustrated, this cold air is forced to take roughly the direction indicated by the dotted arrow, so that at the top, and before the hot gases strike the overhead tubing, they are deflected in an approximately horizontal direction and distributed over the cross-section of the column of hot gases. This cross-current also effects a mixing of the combus-

tion gases which improves the combustion in the combustion chamber. Where there is no such lateral movement of the cold air, it is apt to go up in a continuous channel. Coal dust firing and other methods of introducing fuel may also be used here with advantage in connection with the improved construction.

5 The hot water and steam from the tubes 20 and 21 may be passed to the drum 7 without 10 going through the headers 5 and 6; and various other arrangements of the circulation may be made.

15 Various modifications may be made by those skilled in the art without departing from the invention as defined in the following claims.

What I claim is:—

1. A boiler having approximately horizontal overhead tubing and a furnace with a 20 high rear wall which is offset beyond the rear ends of the overhead tubes, with an arch at the upper end of said rear wall spanning the distance between it and the rear ends of said overhead tubes, said offset rear wall extending 25 upward vertically practically to the rear ends of the overhead tubes and extending downward well below the level of the front wall and forming a comparatively high combustion chamber of the full width of the overhead bank of tubes, of greater length 30 than said tubes throughout substantially the full height of the chamber and of greater depth at the back than at the front.

2. A boiler having approximately horizontal overhead tubing and a furnace having a comparatively high combustion chamber the rear wall of which is vertical and offset beyond the rear ends of the overhead tubes, with an arch at the upper end of said rear 35 wall spanning the distance between it and the rear ends of said overhead tubes, in combination with a stoker extending from the front to the rear of the furnace, the offset rear wall extending vertically practically up to the 40 rear ends of the overhead tubes to form a comparatively high combustion chamber of the full width of said tubes and of greater length throughout substantially the full height of the chamber so as to effect thorough combustion and uniform 45 admixture of the gases.

3. A boiler having approximately horizontal overhead tubing and a furnace with a high rear wall which is offset beyond the 50 rear ends of the overhead tubes, with an arch at the upper end of said rear wall spanning the distance between it and the rear ends of said overhead tubes, said offset rear wall extending upward vertically practically to the 55 rear ends of the overhead tubes and extending downward well below the level of the front wall and forming a comparatively high combustion chamber of the full width of the overhead bank of tubes, of greater length 60 than said tubes throughout substantially the full height of the chamber and of greater depth at the back than at the front, said rear wall and arch including water tubes extending from the bottom of the wall up to the rear end of the overhead tubes.

65 4. A boiler having approximately horizontal overhead tubing and a furnace having

full height of the chamber and of greater depth at the back than at the front, said rear wall including vertical water tubes exposed to the radiant heat of the burning fuel.

70 4. A boiler having approximately horizontal overhead tubing and a furnace having a comparatively high combustion chamber the rear wall of which is vertical and offset beyond the rear ends of the overhead tubes, with an arch at the upper end of said rear wall spanning the distance between it and the rear ends of said overhead tubes, in combination with a wall of vertical water tubes lining said rear furnace wall and a stoker extending from the front to the rear of the 80 furnace so that said tubes are exposed to the direct radiant heat of the burning fuel, the offset rear wall extending vertically practically up to the rear ends of the overhead tubes to form a comparatively high combustion chamber of the full width of said tubes 85 and of greater length throughout substantially the full height of the chamber so as to effect thorough combustion and uniform admixture of the gases.

90 5. A boiler having approximately horizontal overhead tubing and a furnace having a comparatively high combustion chamber the rear wall of which is vertical and offset beyond the rear ends of the overhead tubes, with an arch at the upper end of said rear wall spanning the distance between it and the rear ends of said overhead tubes, in combination with an ash pit located at the bottom of said offset rear wall and a stoker extending from the front of the furnace to said ash pit, the offset rear wall extending vertically practically up to the rear ends of the overhead tubes to form a comparatively high combustion chamber of the full width of said tubes 100 and of greater length throughout substantially the full height of the chamber so as to effect thorough combustion and uniform 105 admixture of the gases.

110 6. A boiler having approximately horizontal overhead tubing and a furnace with a high rear wall which is offset beyond the rear ends of the overhead tubes, with an arch at the upper end of said rear wall spanning the distance between it and the rear ends of 115 said overhead tubes, said offset rear wall extending upward vertically practically to the rear ends of the overhead tubes and extending downward well below the level of the front wall and forming a comparatively high 120 combustion chamber of the full width of the overhead bank of tubes, of greater length than said tubes throughout substantially the full height of the chamber and of greater depth at the back than at the front, said rear wall and arch including water tubes extending from the bottom of the wall up to the rear end of the overhead tubes.

125 7. A boiler having approximately horizontal overhead tubing and a furnace having

a comparatively high combustion chamber the rear wall of which is vertical and offset beyond the rear ends of the overhead tubes, said rear wall including vertical water tubes and a stoker extending from the front to the rear of the furnace so that said tubes are exposed to the radiant heat of the burning fuel, the offset rear wall extending vertically practically up to the rear ends of the over-

head tubes to form a comparatively high 10 combustion chamber of the full width of said tubes and of greater length throughout substantially the full height of the chamber so as to effect thorough combustion and uniform admixture of the gases. 15

In witness whereof, I have hereunto signed my name.

JAY A. FREIDAY.
